UNITED STATES PATENT OFFICE.

WILLIAM H. MORGAN, OF WARE, MASSACHUSETTS.

LAP-SMOOTHING DEVICE FOR COTTON-PICKERS.

SPECIFICATION forming part of Letters Patent No. 463,533, dated November 17, 1891.

Application filed November 22, 1890. Serial No. 372,284. (No model.)

To all whom it may concern:

Be it known that I, WILLIAM H. MORGAN, a citizen of the United States, and a resident of Ware, in the county of Hampshire and State 5 of Massachusetts, have invented certain new and useful Improvements in Lap-Smoothing Devices for Cotton-Pickers; and I do hereby declare that the following is a full, clear, and exact description of the invention, which will 10 enable others skilled in the art to which it appertains to make and use the same, reference being had to the accompanying drawings, which form a part of this specification.

My invention relates to lap-smoothing devices for cotton-pickers.

In cotton-pickers as now ordinarily constructed a lap of cotton is formed therein, being subjected to the action of revolving beaters for the purpose of opening the same or 20 picking the fibers apart and relieving them of dust, dirt, and other foreign substances. The lap is then fed to collecting-cages, which are provided with revolving cage-rolls, which form, smooth, and straighten the laps. From 25 these cages the lap is conducted to and wound upon calendering-rollers, preparatory to being subjected to the action of the carding-engine.

It frequently happens, especially in damp 30 or muggy days, that the laps wound upon the calendering-rolls would cleave and stick together, so that when unwound a portion would split and run into the carding-machine double, causing uneven and inferior work, extra labor, and waste of material. This is owing 35 principally to the irregular manner in which the lap is laid by the cage-roll.

The object of my invention is to obviate the above defect by providing simple, economical, and efficient apparatus, which will 40 lay the lap coming from the picker in a smooth, even, regular, and uniform manner, whereby there will be no danger of sticking when wound upon the calender-rolls.

The invention consists in the novel construction and arrangement of parts hereinafter fully described, and specifically pointed out in the claim.

In the accompanying drawings, Figure 1 is 50 a central longitudinal sectional view showing

a cotton-picker and a collecting-cage constructed according to my invention. Fig. 2 is a perspective view of the cage-roller, also showing the fiber race and smoother.

In the said drawings the reference-numeral 1 designates the frame of the apparatus, 2 the picker-cylinder casing, and 3 the revolving beater located therein, which constitutes the picker. This picker may be of any of the various forms or constructions now in general 55 use, and forms no part of my invention.

The numeral 5 designates the cage-roll, consisting of a cylinder of wire-gauze or perforated metal, connected with end bands or rings 5^a, which in turn are connected with the 60 shaft 6 by means of the radial arms 7. In front of the cage-roll is located a fiber-race 4, consisting of a transverse plate of metal, leather, or other suitable material, the ends of which are secured to the frame 1, and above 65 the cage-roll is a casing 10. Instead of the cage-roll being made of wire-gauze or perforated metal, it may consist of parallel transverse wires secured to the wings 5^a, with spaces therebetween. A fan is to be connected with the cage for the purpose of drawing 70 the fiber onto the surface of the cage-roller.

Connected with the race-plate 4 is a smoother, consisting of a series of curved 75 tongues 8, which project upwardly and rearwardly and lie upon the periphery of the cage-roll. There is a small space or interval 9 between each two adjacent tongues, and the 80 tongues may be made of metal, leather, or other suitable material, and connected with the race-plate or frame in any convenient manner. They may be made separately or they 85 may be formed integral with said plate, and they may be rough or smooth, according to the 90 fiber being operated upon. At this junction of the race-plate and casing is a feed-opening 95 10^a.

Intermediate the race 4 and the picker is an 95 endless belt 12 for conveying the fiber from 100 the feeders 13 to said race, said belt passing over rollers 12^a, journaled in the frame 1. The feeders may consist of a series of fingers mounted upon shafts 14, revolving in opposite directions and located in close proximity to 100

the delivery-opening in the picker-casing. These features, however, form no part of my invention.

The operation is as follows: The lap of fiber 5 as it comes from the picker is caught by the feeders and fed to the conveyer-belt, which carries it to the race 4, from which it is fed to the cage. As it enters the cage through opening 10 it comes upon the smoother, the spaces 9 10 allowing the fiber to come in contact with the cage-roll, which will draw it along the tongues 8 into the cage, from whence it will engage and be carried to the calender-rolls. By means of this smoother the fiber is laid down smooth 15 and regular and the finished lap is uniform throughout, allowing it to be wound upon the calender-rolls and unwound therefrom without liability of cleaving or splitting.

Suitable driving-pulleys and belts will be

connected with the beater and cage-rolls for 20 imparting motion thereto, as is usual, and therefore need not be illustrated.

Having thus described my invention, what I claim is—

An attachment for cotton-pickers, consisting of a reticulated roll and a casing, a fiber-race located in front of said roll, and a series of tongues with spaces therebetween connected or formed with said race and lying upon the periphery of said roll, substantially as described.

In testimony that I claim the foregoing as my own I have hereunto affixed my signature in presence of two witnesses.

WILLIAM H. MORGAN.
